(57) CLAIM

The ornamental design for a personal draught appliance, as shown and described.

DESCRIPTION

FIG. 1 is an isometric view of the personal draught appliance showing environmental features in dashed lines.

FIG. 2 is an isometric view of the personal draught appliance in FIG. 1.

FIG. 3 is a left side view of the personal draught appliance of FIG. 1.

FIG. 4 is a top view of the personal draught appliance of FIG. 1.

FIG. 5 is a bottom view of the personal draught appliance of FIG. 1.

FIG. 6 is a front view of the personal draught appliance of FIG. 1; and,

FIG. 7 is a rear view of the personal draught appliance of FIG. 1.

The broken lines showing portions of the home draught appliance are included for the purpose of illustrating environmental structure and form no part of the claimed design.

1 Claim, 4 Drawing Sheets
